UNITED STATES PATENT OFFICE.

HERBERT V. SHEPPARD, OF WORCESTER, MASSACHUSETTS.

DESIGN FOR A CORN-PLASTER.

53,939.

Specification for Design.

Patented Oct. 7, 1919.

Application filed January 8, 1917. Serial No. 141,333. Term of patent 14 years.

To all whom it may concern:

Be it known that I, HERBERT V. SHEPPARD, a citizen of the United States, residing at Worcester, in the counter of Worcester and Commonwealth of Massachusetts, have invented a new, original, and ornamental Design for a Corn-Plaster, of which the following is a specification, reference being had to the accompanying drawing, forming part thereof.

The figure is a plan view of a corn plaster, showing my new design.

Copies of this patent may be obtained for five cents each, by addressing the "Commissioner of Patents, Washington, D. C."

My new design consists in forming a plaster in the shape of a heart having an opening through the center, as shown.

I claim:

The ornamental design for a corn plaster, as shown and described.

HERBERT V. SHEPPARD.
